UNITED STATES PATENT OFFICE

HENRY C. QUESENBERRY, OF DELTON, VIRGINIA

JACK ABUTMENT

Application filed December 22, 1928. Serial No. 327,901.

This invention aims to provide an abutment for a jack, the construction being such that the abutment may be shifted along to any desired place and there be held securely and firmly. Another object of the invention is to provide a construction whereby the abutment will be rendered strong to resist the thrust of the jack, and at the same time, have an increased hold on the member to which the jack is to be applied.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described, and claimed, it being understood that, within the scope of what is claimed, changes in the precise embodiment of the invention shown can be made without departing from the spirit of the invention.

In the accompanying drawings:—

Figure 1 shows in side elevation, a device constructed in accordance with the invention, and applied to one of the many uses of which it is capable;

Figure 2 is a detail enlarged from Figure 1; Figure 3 is a front elevation;

Figure 4 is a cross section showing the abutment in top plan;

Figure 5 is a cross section showing the abutment in bottom plan.

The device forming the subject matter of this application is capable of many uses in the hands of bridge carpenter or other mechanic, and it is not possible to mention, and much less to show, all of the uses to which the device claimed may be put. A single illustration will be employed, and that will be enough, since a skilled mechanic will be capable of using the device in a way which will

solve the particular problem that happens to be before him. As an illustration then, and not as a limitation, there is shown in Figure 1, a sub-structure 1 which may be a sill from which extends a vertical post 2.

Suppose that it is desired to remove the ver-

tical post 2. Then it is the practice to support, by means of an inclined brace 3, whatever the post 2 may carry, the post 2 being pulled out and being replaced by a new post. It is necessary to shove up the brace 3 so that it will support the super-structure and a jack 4 is employed for this purpose, the jack being mounted on a footing 5 carried by the sub-structure 1. Considerable difficulty has been experienced in providing some means whereby the jack 4 can get a good hold on the inclined brace 3, and the present invention aims to provide a way out of this difficulty.

In carrying out the invention, there is provided a U-shaped metal bracket 6 including a straight end piece 7 and straight parallel side arms 8, disposed at right angles to the end piece 7 and connected thereto. The side arms 8 terminate in threaded stems 9 which pass removably through a yoke bar 10. Nuts 11 are threaded on the stems 9 and engage the yoke bar 10. The threads on the stems 9 preferably are cut square, so as to withstand hard use.

The end piece 7 of the bracket 6 is supplied with an outstanding foot 12, which is roughened on its lower surface, as shown at 14, so that the jack 4 can get a good hold on it. There is a hole 15 in the foot 12, so that scaffolding (not shown) or anything else, may be bolted to the foot 12. The end piece 7 of the bracket 6 has an upstanding extension 16 located at right angles to the foot 12. Buttresses 17 connect the extension 16 with the end piece 7 and with the foot 12.

When the nuts 11 are tightened up, the brace 3 will be bound tightly between the end piece 7 and the yoke bar 10, and the bracket 6 will be held securely on the brace. The upper end of the jack 4 is engaged with the foot 12, and by feeding the jack upwardly, the brace 3 will be thrust upwardly as and for a purpose readily understood by any bridge carpenter or wrecker.

The extension 16 aids in withstanding the thrust of the jack 4 and keeps the end piece 7 of the bracket 6 from biting into the brace 3 under the thrust of the jack. The extension, moreover, forms a place of anchorage for the buttresses 17, and the buttresses, of course, re-

inforce the foot 12 and enable it to withstand the thrust of the jack 4.

As has been stated in the opening portion of this specification, the bracket 6 may be used for many purposes other than the one shown in the drawings.

Having thus described the invention, what is claimed is:—

In a jack abutment, a substantially U-shaped bracket comprising side arms located in a common plane, and an end piece connecting the arms, a jack-engaging foot outstanding from the end piece parallel to said plane, an extension projecting from the end piece at right angles to said plane and having its inner surface flush with the inner surface of the end piece, the extension constituting means for preventing the bracket from tilting under the thrust of a jack and biting into the member that is straddled by the bracket and to which the jack is to be applied, a reinforcing buttress joined to the foot and to the extension, and clamping means cooperating with the extension and the end piece to hold the bracket in place on the said member to which the jack is to be applied, the clamping means being mounted on the side arms of the bracket.

In testimony that I claim the foregoing as my own, I have hereto affixed my signature.

H. C. QUESENBERRY.
